PAPERHANGER'S TABLE AND
STRAIGHTEDGE

Maurice N. Bucht, Wakefield, Mass.

Application May 21, 1941, Serial No. 394,480

14 Claims.

(Cl. 164—78)

This invention relates to tables and straight edges such as are used by paperhangers to trim wall paper and prepare it for hanging. Such tables are of considerable length and the straight edge is approximately the length of the table.

One object of the present invention, therefore, is to provide a table which can be folded for transportation and storage and to provide a sectional straight edge which can be reduced in length when not in use and may be supported and enclosed by the table when the table is folded.

A further object is to provide a hinge connection for the table portions which may be adjusted as necessary to maintain the table sections in accurate alignment when the table is extended for use.

Still another object is to provide on the table adjustable stops for cooperation with the straight edge to facilitate the proper placing of the straight edge with relation to the margins of the paper which must be trimmed off and which often are of different widths along opposite side edges of the paper.

For a more complete understanding of this invention, reference may be had to the accompanying drawings in which

Figures 1 and 2 are perspective views of the table in condition of use and folded, respectively.

Figure 1a is a perspective view showing a modified form of paper edge guide.

Figure 3 is a detail section to a larger scale on line 3—3 of Figure 1.

Figure 4 is a detail section on line 4—4 of Figure 3.

Figure 5 is an exploded perspective view of a hinge and its mounting.

Figure 6 is an exploded perspective view showing a straight edge table stop and its relation to the table.

Figure 7 is a top plan view of the straight edge.

Figure 8 is a fragmentary top plan view similar to a portion of Figure 7, but showing the straight edge parts disassembled.

Figure 9 is a detail section on line 9—9 of Figure 7.

Figure 10 is a detail section on line 10—10 of Figure 9.

Figure 11 is a fragmentary perspective view showing one cooperative relation between the straight edge and a table stop.

Figures 12 and 13 are fragmentary top plan views showing the two cooperating positions of

the straight edge with relation to the table for trimming off opposite margins of the paper.

Referring first to Figures 1 to 3, there is illustrated a table comprising two sections 1 hinged together by hinges 2 so that they may be brought into a single plane as shown in Figure 1 or may be folded up together as shown in Figure 2. The remote end portions of the sections 1 may be provided with folding supports 3. As shown such supports comprise the leg elements 4 braced crosswise of the table by the brace members 5 and adapted to be held vertically in table-supporting position by foldable toggle links 6. This arrangement permits the legs 4 to be folded in pairs close against the under sides of the sections 1, which may then be folded about the axis of the hinges 2 into the form shown in Figure 3, the sections of the table 1 being then somewhat spaced apart to provide room for receiving the legs 4 between them adjacent to their side margins and to leave a space centrally within which other parts such as the sectional straight edge, to be later described, may be housed, so that the table forms an enclosing package within which other parts may be placed for convenience of transportation or storage.

In order to provide for spacing between the table portions 1 when folded, the hinge axis is spaced below the lower face of the table portions 1, and as such a table is subject to hard usage in service and it is necessary that the portions 1 be held rigidly in a common plane when the table is opened for service, means are provided for adjusting the portions 1 with respect to each other and to the hinges so that inaccuracies in alignment may be corrected from time to time as they appear. For this purpose each hinge 2 is shown as formed of two angle portions 10 and 11, which, when the table is open, have substantially aligned horizontal legs 12 and 13 and angularly related legs 14 and 15 which are held together as by the hinge pintle 16. One of these angle members, as 10, is shown as rigidly fixed to the lower face of one of the table sections 1 as by the screws 17 and may be provided with an anchoring lug 10a. The horizontal leg 18 of the other angle member 11 is arranged for adjustable securing to the other table portion 1. As shown this securing comprises a metal base plate 20 which may be secured rigidly to the lower face of the table section 1, and it is preferably provided with upstanding ears 22 which engage in suitable slots in the table section and tend to anchor the plate 20 firmly in position. It may be set within a recess in the lower face of its table section to

bring the lower face of the plate 20 into the plane of the lower face of the other table section 1 when the table is extended for use. This plate 20 is shown as provided with a plurality of screw holes 23 through which screws 24 may be passed to hold the plate 20 firmly in position. It is also shown as provided with two holes 25 and at its end remote from the other table section 1 a downturned perforated ear 26. The holes 25 may have passed therethrough the shanks of bolts 30, the heads 31 of which may be seated in recesses cut into the lower face of the table section. The shank 32 of each bolt 30 extends through a hole 25 and through a slot 35 through the horizontal leg 18 of the angle member 11. A nut 36 threaded on the lower end of each bolt 30 secures the angle member 18 in adjusted position with respect to the table section to which it is secured. Adjustment of these parts may be afforded by the adjustment of a pair of nuts 40 engaging a bolt 41 secured in an ear 42 of the angle member 18 and passing through a hole 43 in the ear 26, there being one of the nuts 40 on each side of the ear 26. By this means the hinge connection to the table may be adjusted from time to time as is necessary in order to maintain the table sections 1 in registry and in proper alignment when the table is unfolded.

Each of the table sections is also provided with a paper supporting and guide member 50, these members, as shown, being arranged along the adjacent edges of the corresponding table portions 1 on the top faces thereof and each having a raised margin or edge gage 51 against which the edge of the paper may be engaged. Each member 50 may also be provided on its lower face with a longitudinal stiffening rib 52 which may be seated in a groove 53 in the top face of the table portion.

Commonly lateral extensions for the table are provided, and of course such extensions may be employed in the arrangement shown but as they are old and well known they have not been illustrated in the drawings.

The paper to be trimmed is brought up with its edge against the element 51 and a straight edge is then applied over the paper at the required distance from the element 51 to facilitate trimming off the margin of the paper to a width determined by the margin outwardly of the design portion of the paper which is to appear after the paper is hung.

The straight edge has many uses in connection with the hanging of paper aside from its use in connection with the table when paper is being trimmed, so that it is important that the straight edge be entirely separate and detached from the table and that it have no parts attached thereto or projecting therefrom which might interfere with any of the uses for which the paperhanger may wish to employ it. There are also occasions when a separate straight edge detached from the table is desirable even for trimming, since the straight edge is then capable of free adjustment on the table or on the floor rather than having only the limited adjustment which would result should the straight edge at any time be carried by or fixed to the table.

It is also desirable that the top face of the straight edge be free from obstructions which would interfere with or prevent free movement of the trimmer from one end to the other of the straight edge and to be put on or removed at either end of the straight edge.

In accordance with the present invention, there-

fore, the straight edge is unattached to the table, but is provided with parts for cooperation with parts on the table so arranged that these straight edge parts do not interfere with any other use of the straight edge for which the paperhanger may find it suitable or with the free use of the trimmer.

Commonly the margins to be trimmed off are of different widths along opposite side edges of the paper, and in accordance with this invention means are provided by which proper setting of the straight edge may be rapidly effected for each of these edges to be trimmed.

As the straight edge is a part of the paperhanger's equipment which must be transported to and from each particular job and as this straight edge needs to be almost as long as the table itself, provision is made in accordance with this invention by which the straight edge may be reduced in length and carried within the casing formed by the folded table. For this purpose it is shown as made of two aligned sections 60 and 61 and for the purpose of increasing the length of contact between these aligned sections to facilitate accurate and rigid attachment of the two together, their line of juncture is shown as diagonal to the length of the straight edge. It should, however, be understood that the juncture may be made at any angle to the length of the straight edge desired.

The straight edge shown includes a central wooden core portion 62 enclosed in a sheet metal sheath or protecting cover portion 63 which passes around the bottom face of the straight edge and covers the side edges and a portion of the top. As shown this metal covering 63 partially overlies a slot 64 in the top face of the straight edge core adjacent to one side edge. This provides a track-way for a cutter carriage (not shown) which may be caused to traverse the length of the straight edge and trim off the paper, either closely adjacent to the side edge of the straight edge or at a predetermined distance therefrom as may be found most convenient. As such cutter carriages are old and well known such carriage is not shown herein, and if desired it may be omitted, the operator then using a hand knife and cutting along the edge of the straight edge.

For the purpose of securing the sections 60 and 61 together, they may be provided with mating pins 65 and perforations 66 in their adjacent metal end portions. These pins and perforations accurately locate the straight edge sections with respect to each other and they may be secured together as by a screw 67. The head 68 of this screw, which as shown may be circular and provided with radial perforations 69 suitable for engagement with a rod or other tool, is seated within a slot 70 in one of the straight edge sections as 60, and its shank extends through a perforation 71 in this section, so that the threaded extremity 72 of the screw may engage in a matingly threaded hole 73 in the other straight edge section 61. After bringing the two straight edge sections together end for end, inserting the pins 65 in the holes 66, the screw 67 may be started within the hole 73 and then by turning the screw the straight edge parts may be rigidly secured in proper position.

The means for locating the straight edge on the table quickly with reference to the particular margin width of the paper which is to be trimmed off may comprise two pairs of table stop elements 75 and 76 arranged in two sets. Each of these stop elements may comprise an angle abutment member having a vertical lug 77 slotted length-

wise as at 78 and a horizontal stop portion or leg 79. These abutments may be positioned back to back with their stop elements 79 facing in opposite directions and their vertical legs 77 may be inserted through slots 80 in the top face of the table. For accuracy in positioning these parts, a wear plate 81 may be set into the top face of the table adjacent to each end, these wear plates carrying the slots 80, and along the margins of the slots 80 scale lines 82 may be marked to aid in positioning the two abutments. They are arranged to be secured in position with the stop edges 83 of the table abutments positioned at the desired distance from the guide member 51 on the table, and for this purpose an angle bracket 85 having an inwardly directed leg 86 and a perforated leg 87 may be secured to the lower face of the table, this being done as shown by passing screws 88 through holes in the leg 87 and into a reinforcing marginal member 89 of the table and through a horizontal perforated ear 86a projecting from the leg 86. A bolt 90 secured to and projecting from the leg 86 and through the slots 78 of the table abutments permits these parts to be clamped together by tightening a wing nut 91 on the bolt 90. The edges 83 of the table abutment members are adjusted along the scale lines 82, one of these abutment members being adjusted for its stop to correspond with the margin on one side of the paper to be trimmed and the other with its stop being adjusted in accordance with the width of the margin along the other edge of the paper, and the abutments of each pair correspondingly positioned in two sets are adjusted for the same margin spacing at both ends of the table. Abutments on the lower face of the straight edge spaced equally to the spacing of the table abutments of each set may then be brought selectively into engagement with the table stops of either selected set thereby to readily position the straight edge in accordance with the particular edge of the paper to be trimmed at any particular time.

The abutments on the straight edge are shown as positioned adjacent to opposite ends thereof and as shown each comprises an arm 95 carried by a squared shaft 96 journaled between one edge portion 97 of the metal cover 63 and at the other end in a bracket 98 secured to the plate portion 63 and located within a recess 99 in the filler strip 62. As shown the portion of the cover plate 63 intermediate to the side edges of the straight edge is raised, defining a pair of supports 100 along opposite edges of the straight edge and which rest upon the paper overlying the table or on the table itself. The arm 95 may extend downwardly adjacent to one of these supports 100 and it may be held downwardly pressed against the table top beyond the ends of the paper as by a torsion coil spring 101 secured at one end to the arm 95 and at the other to the plate 63. Should it be desired not to use the arms 95, each may be swung up out of the way into the dotted line position of Figure 10 where it may be held as by a set screw 102 which may be brought up against one face of the squared shaft 96. This arm 95 may be brought up against either of the stop faces of the table abutments, it being shown as brought up against the inner of these abutments in Figure 11 at one end of the table. The straight edge abutment at the opposite end of the straight edge will then engage with the outer abutment at the other end of the table and with the abutments properly adjusted the outer edge of the straight edge will define a marginal space for cutting indicated at

x in Figure 12 between it and the guide member 51. By moving the straight edge endwise, the stop arms 95 may be brought up against the edges of the other table abutments of each pair as shown in Figure 13 so that the outer edge of the straight edge defines with the guide member 51 a different marginal space Y. Thus by merely shifting the straight edge slightly it may be brought up against the table stops defining the proper marginal width for either edge of the paper. The straight edge abutments may be brought up against the edges of either selected set of table abutments remote from the guide member 51, as shown in Figures 12 and 13, so that the bringing of the straight edge into either of its stopped positions acts to press the paper in the direction to bring its edge against the guide member 51.

In order to support the straight edge in convenient position for the paperhanger in placing or removing the paper from the table, the supporting table legs 4 may be provided with the hinged bars 110 which may rest on pins 111 when in operative position to support the straight edge or may be rocked upwardly to come within the outlines of the folded table when it is in the condition of Figure 2.

In Figure 1a a modified construction of edge gage is shown which is made from standard metal parts. The top face of this gage is formed by a metal plate 120 secured along the side portion of each table section, over the top edge of which extends one flange 121 of a channel member 122, the lower flange of which engages in a slot 123 in the edge of the table section 1. The plate and channel may be secured as by screws to the table section. The inner edge of the flange 121 then acts as the edge gage in place of the element 51 of the member 50, and as the flange 121 overlies the edge of the plate 120, it acts to hold down this edge and avoids the necessity of securing the plate 120 down by screws or other means in positions which might present an uneven cutting surface and thus impede free and smooth cutting action of the trimming knife or cutter.

It will be noted that the table stops do not interfere with the free sliding of the straight edge over the surface of the table, except when the straight edge is so positioned that its stops are in proper relation to engage one or the other set of table stops. Neither set of table stops interferes in any way with the functioning of the other set and the straight edge may overlie the table stops of both sets at the same time.

From the foregoing description of an embodiment of this invention, it should be evident to those skilled in the art that various changes and modifications might be made without departing from the spirit or scope of this invention.

I claim:

1. In combination with a table having a guide member against which the edge of paper may be engaged, two pairs of spaced stop members adjustably carried by said table spaced from said guide member and offset from each other in the direction of spacing, and a straight edge wholly detached from said table but which may be supported thereon and having means cooperating selectively with either pair of said stop members when said straight edge is applied to the paper on said table to define a marginal portion of said paper of a width dependent on the adjustment of the selected pair of said stop members.

2. A table having a guide member against which the edge of paper may be engaged, said table hav-

ing a pair of spaced slots therethrough extending transverse to said guide member, a pair of angle abutment members each having a horizontal stop leg adapted to overlie said table and a vertical leg extending through said table slot, and means engaging said vertical leg for securing said member to said table with said stop lug spaced a determined distance from said guide member in position to define a location for a straight edge engaging said stop legs and defining a margin for the paper with respect to said guide member.

3. In combination with a table having a guide member against which the edge of paper may be positioned, two spaced pairs of abutment members relatively offset in the direction of their spacing and carried by said table, the abutment members of each pair being adjustably fixed in spaced relation to said guide member and at different points along the length thereof, and a straight edge wholly detached from said table but which may be supported thereon and having a pair of longitudinally spaced abutments for engagement with the table abutments, the spacing of said straight edge abutments being equal to the spacing of the corresponding table abutments of each pair to permit the corresponding table abutments of each pair to determine the spacing of said straight edge from said guide member.

4. The combination with two members, one comprising a table and the other comprising a straight edge separate from said table but which may be supported thereon, one of said members having a pair of spaced abutments spaced back from one edge of said one member, and the other of said members having two pairs of abutments in offset relation to each other with respect to the spacing of said abutments, the abutments of each pair being spaced substantially equally to the spacing of the abutments on said one member, said pairs of abutments having stop portions and with which the abutments of the other of said members may be engaged, the stop portions of the abutments of said two pairs being positioned at different distances from one edge of said other member whereby an edge of said straight edge may define with an edge of said table a pair of margins of different widths depending upon which pair of said two pairs of abutments on said other member is engaged by the abutments of said one member.

5. The combination with a table having a guide member against which the edge of paper may be positioned, two spaced pairs of abutment members carried by said table, the abutments of the two pairs being offset in the direction of spacing said abutment members having edges remote from said guide member serving as stops, and the stop edges of the abutments of two pairs being positioned at different distances from said guide member, of a straight edge wholly detached from said table but which may be supported thereon and having abutments spaced correspondingly to the spacing of the table abutments of each pair for selective engagement with the stop faces of the table abutments of one or the other pair by motion of said straight edge toward said guide member to define by said straight edge trimming margins for the paper of either of two different widths depending upon which pair of table abutments is engaged by said straight edge abutments.

6. In combination, a table having a guide member extending therealong on its top face, and a slot extending through said table transverse to said guide member, a pair of abutment angles each having a slotted vertical leg for extending into

said slot and a horizontal leg for engagement with the top face of said table, said horizontal legs extending away from each other, a bracket secured to the lower face of said table, and a fastener extending from said bracket through slots of said vertical legs for securing said abutments in adjusted positions with the horizontal legs forming stops on the top of said table for locating a straight edge with relation to said guide member.

7. In combination, a table, a pair of abutments projecting from the top face of said table, a straight edge wholly detached from said table but which may be supported thereon and having a pair of spaced supports for engagement with the top of said table, said straight edge having abutments between said supports for engagement with said table abutments for determining the location of said straight edge on said table.

8. In combination, a table, a pair of abutments projecting from the top face of said table, a straight edge wholly detached from said table but which may be supported thereon and having a pair of spaced supports for engagement with the top of said table, said straight edge having abutments between said supports for engagement with said table abutments for determining the location of said straight edge on said table, certain of said abutments being adjustably mounted for movement between operative and inoperative positions.

9. In combination, a table, a pair of abutments projecting from the top face of said table, a straight edge wholly detached from said table but which may be supported thereon and having a pair of spaced supports for engagement with the top of said table, said straight edge having abutments between said supports for engagement with said table abutments for determining the location of said straight edge on said table, said straight edge abutments being angularly adjustable between operative and inoperative positions.

10. In combination, a table having a guide member, a pair of abutments projecting from the top face of said table a predetermined distance from said guide member, a straight edge having a pair of spaced supports for engagement with the top face of said table, said straight edge having abutments between said supports for engagement with said table abutments for determining a location of said straight edge on said table and with reference to said guide member.

11. In combination, a table, a metal plate secured to the top face of said table along one edge, and a member having a top flange extending inwardly over the outer edge of said plate and a depending portion secured to the side of said table, said flange serving to hold the outer edge of said plate in position and to act as an edge gage.

12. The combination with a table having a guide member against which the edge of paper may be positioned, two spaced pairs of abutments carried by said table, the abutments of each pair being fixed in spaced relation to said guide member and at different points along the length thereof, of a straight edge wholly detached from said table but which may be supported thereon, and means spacing the lower face of said straight edge above said table to permit said straight edge to be moved along the top of said table without interference from said abutments, said straight edge having a pair of elements spaced lengthwise thereof in accordance with the spacing of the abutments of each pair, which elements may be brought by motion of said straight edge into contact with

either of said pairs of abutments to define either selected of two widths of margin depending on the pair of abutments selected, between an edge of said straight edge and said guide member.

13. The combination with a table having a guide member against which the edge of paper may be positioned, a pair of abutments on the top face of said table spaced therealong, of a straight edge wholly detached from said table but which may be supported thereon, and means spacing the lower face of said straight edge above said table to permit said straight edge to be moved along the top of said table without interference from said abutments, said straight edge having a pair of elements spaced lengthwise thereof in accordance with the spacing of said abutments which elements may be brought by motion of said straight edge into contact with said abutments to define a width of margin between an edge of said straight edge and said guide member.

14. In combination, a table having a guide member against which the edge of paper may be positioned, two pairs of spaced abutments carried by and projecting above the top of said table and adjustable toward and from said guide member, and a straight edge wholly detached from said table but which may be supported thereon and having spaced supports for engagement with the top of said table and defining between them spaces into which said abutments may project, said straight edge having a pair of elements spaced therealong corresponding to the spacing of the abutments of each pair and which by motion of said straight edge may be moved against the abutments of either pair to determine by the positioning of the pair of abutments chosen the distance between an edge of said straight edge and said guide member.

MAURICE N. BUCHT.
